UNITED STATES PATENT OFFICE.

ROBERT F. SIMMONS AND CHARLES FRANCISCO, OF BROOKLYN, NEW YORK,
ASSIGNORS TO NEW YORK STAMPING COMPANY, OF BROOKLYN, NEW YORK, A
CORPORATION OF NEW YORK.

CURRYCOMB.

1,089,368.

Specification of Letters Patent. Patented Mar. 3, 1914.

Application filed January 13, 1913. Serial No. 741,812.

To all whom it may concern:

Be it known that we, ROBERT F. SIMMONS and CHARLES FRANCISCO, citizens of the United States, residing at Brooklyn, in the county of Kings and State of New York, have invented a certain new and useful Improvement in Currycombs, of which the following is a full, clear, and exact description.

The primary object of the invention is to provide convenient means for permanently attaching flexible handles to the metallic backs of currycombs, but the invention is not limited to its use in connection with any particular construction of handle or currycomb, or to currycombs only. Generally such handles have been applied by means of rivets, although other attaching means have been proposed.

In the present illustration of the invention the metal back of a currycomb is provided with oppositely arranged tongues or flams, which are formed integral with the back, leaving openings in the back through which the ends of the handle are passed, and then these tongues or flams are pressed back so as to grip the ends of the handle between themselves and the adjacent portions of the back; and to further insure the security of the fastenings, the edges of the tongues or flams may be provided with projections, leaving corresponding notches in the adjacent edge from which the tongues or flams are cut, and which projections and notches coöperate to grip the ends of the handle and thus firmly secure it in place, as we will proceed now to explain and finally claim.

In the accompanying drawings, illustrating the invention, in the several figures of which like parts are similarly designated, Figure 1 is a top plan view, with one end of the handle broken away so as to expose the tongue or flam construction, and showing the invention applied to a metallic currycomb. Fig. 2 is an inverted plan view. Fig. 3 is a central cross-section taken through the handle. Fig. 4 is a perspective view illustrating the peculiar construction of a preferred form of teeth.

We will proceed now to explain our invention in detail as applied to one form of currycomb, and in this construction the currycomb is made up of a back 1, having its rim 2 made as a corrugated flange, the

edge of which forms the teeth, some of the 55 teeth, as 3, inclining one way, and others, as 4, inclining in the opposite way, as indicated in Fig. 4, so as to insure a more thorough combing of the animal. Nested within this flanged back are similar concentric 60 cup-shaped pieces 5 and 6, provided with similar toothed edges, and secured within the back and one within the other, as indicated more particularly in Figs. 2 and 3, by means of rivets 7. 65

The back is provided with oppositely arranged slits 8 cut lengthwise of the back, and pairs of parallel slits 9 extending at right angles from the slits 8 so as to leave flexible tongues or flams 10 which as herein 70 shown are turned inwardly, thus leaving slots through which the ends of the leather strap 11 bowed over the back are passed, and then the tongues or flams are bent back toward the original level of the back of the 75 currycomb, thus narrowing the slots and pinching and permanently holding the ends of the handle between the adjacent edges of the slits, as shown more particularly in Fig. 3. To increase the holding efficiency of these 80 flams, they may be made with projections 12 of any sort, here shown as pointed prongs, and the formation of these projections leaves corresponding notches 13 in the adjacent edges of the slits, so that as the tongues or 85 flams are forced or bent back to grip the ends of the strap, the material of the handle is crimped in between the projections on the tongues or flams and the notches and thus an additional security is afforded in the 90 attachment of the handle.

By the construction described a very simple and efficient handle attaching medium is afforded, and one that may be economically made and used. 95

As already stated, the invention is designed primarily for the attachment of leather straps to the metal backs of currycombs, but obviously the handle-attaching means may be applied to other devices than 100 currycombs where useful or available, and the claims herein made are to be so understood. It is also within the invention to make the projections 12 on the opposite edge of the slit 8 and the complementary notches in 105 the tongue or flam.

The formation of the tongues or flams may be modified to suit the form and material of

the handle; the gist of the invention being in the provision of handle-attaching means integral with the back of the article and obviating the necessity of using rivets and other extraneous or applied fastenings. The shape and number of the projections and the corresponding notches and their location may be altered as desired, and indeed the projections and notches may be omitted altogether.

What we claim is:—

1. A currycomb, of substantially the construction described, having a metal back provided with slits and adjacent integral flexible tongues or flams bent away from the level of the metal of the back coincidently with said slits to form slots in said back, and a handle having its ends passed through said slots, said tongues or flams being bent back toward the level of the metal of the back to narrow the slots and thereby pinch and permanently hold the ends of the handle in the slots by and between the adjacent

edges of the tongues or flams and the metal of the back.

2. A currycomb, comprising a series of comb members, and a back formed integrally with one of said comb members and having a pair of flexible tongues or flams cut from and bent beyond the level of said back and forming openings upon opposite sides of the back, and a handle bowed over said back and having its ends passed through said openings, said tongues or flams being bent back toward the level of the back to pinch and permanently hold the handle in said openings.

In testimony whereof we have hereunto set our hands this 11th day of January A. D. 1913.

ROBERT F. SIMMONS.
CHARLES FRANCISCO.
